UNITED STATES PATENT OFFICE.

DUGALD C. JACKSON, OF MADISON, WISCONSIN.

TELEPHONE-TRANSMITTER.

SPECIFICATION forming part of Letters Patent No. 764,055, dated July 5, 1904.

Application filed September 26, 1902. Serial No. 124,962. (No model.)

To all whom it may concern:

Be it known that I, DUGALD C. JACKSON, a citizen of the United States, residing at Madison, in the county of Dane and State of Wisconsin, have invented a certain new and useful Improvement in Telephone-Transmitters, of which the following is a full, clear, concise, and exact description, reference being had to the accompanying drawings, forming a part of 10 this specification.

My invention relates to telephone-transmitters, and has for its object the provision of an improved form of battery-transmitter of the type in which comminuted carbon or 15 equivalent material is interposed between the electrodes.

The particular object of my invention consists in the provision of an improved and simplified chamber within which the comminuted 20 carbon is to be placed.

My invention contemplates the provision of an improved chamber which incloses the electrodes and which permits the relative movement thereof. At the same time the chamber 25 retains the comminuted material in its proper disposition between the electrodes.

I accomplish the objects of my invention by providing a preferably cylindrical wall in the shape of a short tube within which the comminuted carbon is contained. This short tube 30 is preferably lined with insulating material to prevent the direct electrical contact of the carbon with the cylindrical wall. Rigidly secured to the said cylindrical wall and projecting into one end thereof I provide the stationary electrode of the microphone. The movable electrode is connected with the main diaphragm of the transmitter in such a way as to be subject to vibrations caused by sound- 40 waves. I find it desirable to mount the aforementioned cylindrical tube on the frame or casing of the transmitter and to allow the vibrating electrode to have what may be termed a "plunger" action within the said chamber.

In order to permit the movement of this electrode within the said chamber and at the same 45 time to prevent the escape of the confined carbon granules, I find it desirable to provide a bushing or packing-ring for the said plunger, 50 as will be hereinafter more fully set forth.

My invention will be best understood by reference to the accompanying drawings, in which—

Figure 1 is a rear view of the transmitter, the inclosing casing being removed to show 55 the interior construction. Fig. 2 is a vertical sectional view on line 2 2 of Fig. 1, parts of the transmitter being shown in elevation. Fig. 3 is an enlarged sectional view of the microphone and the transmitter-diaphragm. 60 Fig. 4 is a view of the elements shown in Fig. 3 before assembly.

Like parts are indicated by similar characters of reference throughout the different figures. 65

The general characteristics of my improved transmitter are similar to those found in other microphone-transmitters.

I desirably provide an inclosing casing consisting of a rather heavy annular ring 1, to 70 which is secured the back part of the casing 2 and into which is screwed the customary mouthpiece 3. To this annular ring 1 is also screwed the supporting-bracket 4. The diaphragm 5 is provided with a folded rubber ring 6 and is held firmly against the ring 1 of the transmitter-casing by the spring-clips 7, each of which is provided with a rubber sole-piece 8. The bracket 4 is provided with a hole 9 and a set-screw 10, adapted to secure 75 in proper adjustment the stem 11, which carries the back electrode 12. This stem is provided with a threaded disk 13, adapted to screw into the cylindrical tube 14. The tube 14 is thus rigidly connected, through the 80 bracket 4, with the casing of the transmitter. A distance-piece 15, provided with a lining of paper or cloth 16, is also screwed into the tube 14, the distance-piece 15 and the disk 13 being brought into contact, as best illustrated 85 in Fig. 3. A ring 17 also screws into the tube 14 from the other end, this ring 17 being provided on its inside edge with a ring of felt or plush or other cellular material 18.

The front electrode 19, which, like the electrode 12, may desirably be made of polished carbon, is carried by the plunger 20. This plunger is provided with a stem having a shoulder 21 and a threaded portion 22, adapted 95 to pass through a hole in the diaphragm 5 100

and receive a clamping-nut 23. Thus the diaphragm 5 is rigidly connected with the front electrode 19 and the plunger 20, so that the plunger and electrode are subject to sound-vibrations of the diaphragm.

- 5 18. This ring of felt is adapted to fit loosely about the plunger 20, so as to permit a motion of the plunger as inserted by the diaphragm 5 within the chamber containing the comminuted carbon, and at the same time it prevents the escape of the inclosed granules.

15 A wire 25 forms the circuit connection between the insulated transmitter-terminal 26 and the front electrode 19. The back electrode 12 is electrically connected, through the stem 11 and the bracket 4, with the other transmitter-terminal 27.

20 The above description will make clear the operation of my improved transmitter, it being evident that with the vibrations of the diaphragm and front electrode the distance 25 between the electrodes 19 and 12 will be varied. The fact that the electrodes project bodily within the chamber and are partially surrounded by the carbon granules is a desirable feature in that the comminuted material 30 is stirred up by the relative movement of electrodes, and packing is thereby prevented. The plush or felt ring 18, surrounding the plunger 20, allows the utmost freedom for the movement of the plunger with the diaphragm 35 and at the same time effectively confines the carbon granules within their chamber.

While I have herein shown and particularly described the preferred embodiment of my invention, I do not wish to limit myself to the precise construction and arrangement herein shown; but,

40 Having thus described my invention, I claim as new and desire to secure by Letters Patent—

45 1. In a telephone-transmitter, the combination with a front wall, of a diaphragm clamped thereto, a supporting-bracket bridging said wall at the rear thereof, a stem adjustably secured in said bracket and extending forwardly therefrom, a flange at the front end of said stem, an electrode-chamber adjustably engaging said flange and freely suspended therefrom, a rear electrode secured to said flange, 50 a front electrode secured to said diaphragm and extending within said chamber, and a ring of cellular material disposed between the interior walls of said chamber and the periphery of said front electrode.

55 2. In a telephone-transmitter, the combination with a front wall, of a diaphragm clamped thereto, a supporting-bracket bridging across the rear of said wall, a stem adjustably secured in said bracket and extending forwardly

60 therefrom, a threaded flange at the front end of said stem, an electrode-chamber having threaded engagement at its rear end with said flange, a rear electrode secured to said flange, a front electrode secured to said diaphragm and extending within said chamber, and a ring 70 of cellular material disposed between the interior walls of said chamber and the periphery of said front electrode.

75 3. In a telephone-transmitter, the combination with a front wall, of a diaphragm clamped thereto, a supporting-bracket bridging across the rear of said wall, a stem secured in said bracket and extending forwardly therefrom, a threaded flange at the front end of said stem, a tube threaded upon its interior and engaging said flange at its rear end to be freely suspended therefrom, an electrode secured to said flange, a ring having screw-threaded engagement with the forward end of said threaded tube, a front electrode secured to said diaphragm and extending within said tube, and a ring of cellular material secured to said ring and extending between said ring and the periphery of said front electrode.

80 4. In a telephone-transmitter, the combination with a front wall, of a diaphragm clamped thereto, a supporting-bracket bridging across the rear of said wall, a stem secured in said bracket and extending forwardly therefrom, a threaded flange at the front end of said stem, 85 a tube threaded upon its interior and engaging said flange at its rear end to be freely suspended therefrom, an electrode secured to said flange, a ring having screw-threaded engagement with the forward end of said threaded tube, a front electrode secured to said diaphragm and extending within said tube, a ring of cellular material secured to said ring and extending between said ring and the periphery of said front electrode, and a distance-ring 90 engaging said threaded tube and disposed between said ring and the flange.

95 5. In a telephone-transmitter, the combination with a front wall, of a diaphragm clamped thereto, a supporting-bracket bridging across the rear of said wall, a stem adjustably secured in said bracket and terminating at its forward end in a threaded flange, an internally-threaded tube engaging said flange at its rear end, said flange and tube forming an electrode-chamber freely suspended from said stem, a rear electrode secured to said flange, a front electrode secured to said diaphragm and extending within said tube, and a ring of cellular material disposed between the interior of said tube and the periphery of the front electrode.

100 In witness whereof I hereunto subscribe my name this 20th day of September, A. D. 1902.

DUGALD C. JACKSON.
